UNITED STATES PATENT OFFICE.

FREDRICK E. JOHNSON, OF LOS ANGELES, CALIFORNIA.

CAN OPENER.

Application filed June 27, 1924. Serial No. 722,688.

To all whom it may concern:

Be it known that I, FREDRICK E. JOHNSON, a citizen of the United States, residing at Los Angeles, in the county of Los Angeles and State of California, have invented new and useful Improvements in Can Openers, of which the following is a specification.

This invention is a can opener and consists of the novel features herein shown, described and claimed.

An object is to make a can opener which cuts downwardly instead of upwardly.

Other objects and advantages will appear from the drawings and specification.

The drawings illustrate the construction and operation of a can opener embodying the principles of the invention.

Figure 1 is a perspective of the can opener in operation.

Fig. 2 is a side elevation and taken looking in the direction indicated by the arrows 2 in Figs. 1 and 4.

Fig. 3 is a fragmentary bottom plan view as indicated by the arrows 3 in Figs. 2 and 4.

Fig. 4 is an end elevation as indicated by the arrows 4 in Figs. 2 and 3.

The details of construction and operation shown in the drawings are as follows:

The handle bars 1 and 2 are substantially parallel and spaced apart. An integral return bend 3 connects the outer ends of the handle bars 1 and 2. Attaching plates 4 and 5 are formed integral with the handle bars 1 and 2 and extend from the opposite ends from the return bend 3. A pointed piercing prong 6 extends from the attaching plate 5 and an ear 7 extends from the attaching plate 4, the prong and ear being offset toward each other and rigidly secured together by a rivet 8. The cutting plate 9 fits between the attaching plates 4 and 5 and the guide supporting plate 10 fits against the outer face of the attaching plate 5 and

rivets 11 and 12 are inserted through the parts 4, 5, 9 and 10 to hold the parts rigidly together. A cutting edge 13 is formed on the rear side of the plate 9 and extends downwardly and forwardly at an angle of about 45° relative to the handle bars 1 and 2 and terminates in a point 14. A second cutting edge 15 extends from the point 14 upwardly and forwardly substantially at right angles to the cutting edge 13. A straight edge 16 is formed on the front side of the plate 9 substantially at right angles to the handle bars

1 and 2 and extends downwardly nearly to the point 14 and is in line with the point 14.

A fulcrum member 17 is formed between the upper end of the cutting edge 15 and the lower end of the straight edge 16. The fulcrum member 17 is a lip rounded upwardly and downwardly from the lower end of the edge 16 to the upper end of the edge 15, and the lip is bent outwardly, that is, away from the axis of the can 18 which is to be opened, and the inner side of the edge of the lip preferably beveled as at 19. The cutting edges 13 and 15 are formed by inside bevels 20 and 21. A guide bar 22 extends downwardly from the supporting plate 10 to a point substantially on a level with the point 14. A hook 23 extends upwardly and forwardly from the plate 9 above the attaching plates 4 and 5. A bar 24 fits between the attaching plates 4 and 5 back of the plate 9 and is secured in place by a pivot 25. The free end of the bar 24 has a transverse slot 26.

In the practical operation the can top 27 may be pierced by the prong 6 or by the point 14 and the point 14 is inserted through the opening until the fulcrum member 17 engages under the inner side of the rim 28 of the can 18. Then downward movement of the handle bars 1 and 2 will cause the guide bar 22 to engage outside of the rim 28 and the cutting edge 13 will cut the top 27 slightly inside of the rim 28. The cutting is done with a downward motion and the tin 29 projecting inwardly from the rim 28 will be turned inwardly and downwardly over the fulcrum member 17 and hold the fulcrum member against the rim 28. Continued vibration of the handle up and down will continue the operation at each down stroke, the can opener being advanced relative to the can top at each up stroke until the top is severed to the desired extent.

It is not intended that the bevel edge 19 upon the fulcrum member 17 will be sharp enough to cut through the tin, the object being to make the fulcrum member hug the inside of the rim 28. The plate 9 is curved as shown in Fig. 3 as required to operate close inside of the rim 28 and follow a circular path.

The hook 23 is adapted for removing caps from bottles.

The bar 24 is adapted to receive the projecting end upon corned beef cans, sardine cans, and the like, having a separate key for

opening the cans by placing the projecting end in the slot 26 and winding the strip upon the bar.

Various changes may be made without departing from the spirit of the invention as claimed.

I claim:

1. A can opener comprising a handle, a cutter extending downwardly from the forward end of the handle and having a main cutting edge extending from the handle downwardly and diagonally toward the forward end of the can opener toward the handle and a secondary cutting edge extending from the lower end of the main cutting edge and forming a point, a fulcrum member extending upwardly from the secondary cutting edge and offset to engage the inner side of a can rim, and a guide bar extending from the handle outside of the cutter and in front of the main cutting edge to engage the outer side of a can rim, so that when the point has been inserted through a can top inside of the can rim the fulcrum will engage the can rim and the cutter will work on a down stroke of the handle to cut the can top.

2. A can opener comprising a handle having a piercing point at the outer end, a cutter interposed between the ends of the handle comprising a primary cutting edge extending diagonally toward the handle, a secondary cutting edge extending forwardly of the handle and forming a point at the lower end of the cutter, a projection forwardly of the cutter bent to form a fulcrum adapted to engage the inner wall of a can, and a guide bar secured to the side of the handle and extending transversely thereof and parallel to the cutter.

3. A can opener comprising a handle having a piercing point at the outer end, a cutter interposed between the ends of the handle comprising a primary cutting edge extending diagonally toward the handle, a secondary cutting edge extending forwardly of the handle and forming a point at the lower end of the cutter, and a projection forwardly of the cutter bent to form a fulcrum adapted to engage the inner wall of a can.

In testimony whereof I have signed my name to this specification.

FREDRICK E. JOHNSON.
